UNITED STATES PATENT OFFICE.

EMILE BERLINER, OF BOSTON, MASSACHUSETTS.

CARPET.

SPECIFICATION forming part of Letters Patent No. 284,268, dated September 4, 1883.

Application filed July 28, 1883. (No model.)

To all whom it may concern:

Be it known that I, EMILE BERLINER, of Boston, in the county of Suffolk and State of Massachusetts, have invented certain Improvements in Carpeting, of which the following is a specification.

This invention belongs to that class of floor-coverings the pattern of which is formed generally by a number of separate rectangular or triangular pieces, which together form more or less simple geometrical designs, such as the well-known parquet floor. It refers in particular to the successful production of matting parquet—meaning a floor-covering—consisting of a number of sections of straw or other matting, preferably of rectangular form, which are cut out from a whole piece or roll of matting, and when laid on the floor form geometrical designs. The difficulty to cut out such pieces from a whole roll of matting and lay them as parquet on the floor lies in the fact that the cut edges of matting are in a very loose condition and can easily be disarranged, broken, or bent; and to overcome these difficulties I find it necessary either to line the matting with some adhesive glue or cement before cutting it or to fix the loose edges with similar glue or cement after the pieces have been cut, or both.

It will suffice for the illustration of my invention if I confine myself to the production of a simple checker-board pattern of matting parquet; and hence in Figure 1 is shown a roll of matting, A', from which are cut the four square sections a b c d. After they are cut out, their cut edges are dipped into a semi-liquid glue or cement, which, after having hardened, renders the formerly loose edges firm and in a condition to be handled or laid without danger of disarranging the threads or fibers of the material. A piece of cut matting so treated is shown in Fig. 2, in which the section a is shown edged in by a layer of glue or cement, as indicated by the shaded portion. Another method of treating the cut matting is shown in Fig. 3. Here the section b appears lined with a layer of glue or cement, x, and in addition to this a backing, y, of wood, pasteboard, or other cheap and sufficiently stiff material may be added, which

backing, together with the glue and the matting, forms a firm section of parquet matting. It is often necessary to fix the edges even of these lined or backed parquet sections, and I prefer for this purpose the following method, 55 illustrated in Fig. 4: Here the cut section of matting C is glued to the wooden block n. A thick layer of glue or cement, o, is applied to the edge all around the block and the matting, and a strip of felt or other suitable material, P P, is by the glue held and fixed around the whole. The drawings show the operation partially finished. The strip of felt P P may be omitted, however, as the layer of glue o, when hard, will well answer the purpose of making a firm edge. Pieces of matting treated in any of the above-described methods can then be fixed or laid on the floor by means of tacks, pins, or by any of the known methods; and the great advantages of 70 such parquet matting is, not only that no stretching is necessary, but also that, similar to wood parquet, an indefinite number of designs can be produced by combining matting pieces of different color or of different rolls. 75 Such a matting parquet is shown in Fig. 5, which represents a simple checker-board pattern, the pieces a b c d being plain white matting and the pieces e f g h figured matting.

I do not now claim the parquet carpet consisting of pieces of matting which are backed by wood, pasteboard, glue or paste hardened, or similar substances; nor do I now claim the combination of a piece of cut matting with an adhering strip of felt or other pliable material 85 around its edge, because I wish to make these matters part of separate applications; but

I claim—

A parquet carpet consisting of pieces of matting cut from a piece, the cut edges of which 90 are fixed by a glue or cement, substantially as described.

In testimony whereof I have signed my name to this specification, in the presence of two subscribing witnesses, this 25th day of July, 1883. 95

EMILE BERLINER.
